UNITED STATES PATENT OFFICE

HERBERT E. TUCKER, OF SOUTH BEND, INDIANA, ASSIGNOR TO UNIVERSAL DRAFT GEAR ATTACHMENT CO., A CORPORATION OF ILLINOIS

DRAFT GEAR

Original application filed July 9, 1927, Serial No. 204,618. Divided and this application filed July 13, 1928. Serial No. 292,467.

This application is a division of my application, Serial No. 204,618, filed July 9, 1927.

The invention relates to that type of draft gear in which intercalated friction plates and wedging and spring elements are housed within a chambered follower, an opposed follower being of plate or equivalent form; and its objects are to provide in a gear of this type high efficiency, certainty and smoothness of release and for the taking up automatically of the wear of the parts.

A preferred embodiment of the invention is hereinafter described and is illustrated in the accompanying drawing in which

15 Fig. 1 is a vertical, central, longitudinal, sectional view of the gear, the cooperating yoke element being shown in elevation;

Fig. 2 is a detail section on line 2-2 of Fig. 1; and

20 Fig. 3 is a detail section on line 3-3 of Fig. 1.

Any suitable form of coupler extension may be employed, there being shown a common form of yoke 53. At 54, there is shown 25 the outline of the butt of a coupler.

A chambered follower or casing is shown at 46, its closed end being seated against the rear end of the yoke and its forward end facing a plate follower 47 seated against the forward end of the yoke, the casing and follower being normally spaced apart to permit the maximum compression of the gear and to serve as limiting stops when such compression has been reached. Within the casing 30 and adjacent its open end, there are housed two groups of intercalated friction plates respectively adjacent the top and bottom walls thereof. Each group comprises a plurality of comparatively short plates 48 which

35 while being free to move vertically are anchored against longitudinal movement relatively to the casing by means of lateral lugs 51, 51, fitting within channels 52, 52 formed 40 in the side walls of the casing. Each group further comprises a plurality of relatively longer floating plates 49 which are capable of both vertical and longitudinal movement with reference to the casing and which normally project beyond the open end thereof,

but do not make contact with the follower 47.

While there is shown three plates of each of the described forms in each group and they are arranged with one of the shouldered plates adjacent the casing wall, the number and arrangement of the plates may be varied as may be desired.

A thrust member 50 is seated centrally against the follower 47 and is in the form of a block having a stem projecting into the casing 46 and having parallel top and bottom faces. The inner faces of the block 50 are flat to provide a pair of shoulders 93, 93 perpendicular to the axis of the gear.

Between each of the flat faces of the stem 92 and the adjacent group of friction plates, there is interposed a set of wedge elements, each set comprising a friction shoe 97 seated

55 against the inner friction plate and having on its inner face and adjacent its ends wedging faces, that at the outer end of the shoe being inclined inwardly, or toward the axis of the gear and rearwardly or toward the closed end of the casing, while that at the inner end of the shoe is inclined in the opposite direction.

Each set of wedging elements further comprises a plate 98 seated against the stem 92 and having adjacent each end wedging faces which are inclined oppositely from the adjacent wedging faces of the shoe 97. Each set of wedging elements also comprises a pair of triangular wedge blocks 94, 99 which enter between adjacent wedging faces of the elements 97, 98. The block 94 is seated upon 60 one of the shoulders 93 and the block 99 seats against the spring seat 101.

The face 95 of the block 94 which cooperates with the shoe 97 is more acute, to the axis of the gear, than its face 96 which cooperates with plate 98, the wedging face of the elements 97 and 98 with which this block cooperates being, of course, of similar inclination.

The corresponding faces of the block 99 and the wedging faces of the elements 97, 98 are correspondingly inclined.

An axially positioned helical spring 87 reacts between the closed end of the casing 46 and a spring seat 79 having a central stem 70 which bears upon the inner end of the stem

92. A set of helical springs as 89, 91 react between the closed end of the casing 46 and the spring seat 101, which is a unitary structure and is apertured to receive the stem 92 and the stem of the spring seat 79, and in addition to its engagement normally with the wedge blocks 99, 99, also engages the inner ends of the floating friction plates 49. At least one of the friction plates of each 10 group, as the plates 55, 55 is tapered toward its outer end.

There is shown in the drawing a cross bar 82, serviceable in connection with the assembling of the gear elements, but having 15 no function in connection with the operation of the gear. This bar may be entered through suitable slots in the side walls of the casing and passes through the stem 92 which is bifurcated for its reception. The 20 bar is held in place by a tongue 85 projecting from the spring seat 79 into a recess 86 in the bar.

In operation, in buff, the follower 47 moves inwardly carrying with it the thrust member 25 50 and the wedge blocks 94, this movement being resisted by the spring 87, thereby spreading apart the elements 96, 97 and carrying them forward, against the resistance of the springs 89, 91, upon the wedge 30 blocks 99 and thus similarly spreading the inner ends, and placing the two groups of friction plates under high compression.

On initial compressive movement of the gear, the spring seat 101 moves away from the inner ends of the plates 49. When the plate 47 comes in contact with the latter plates, they are moved inwardly with it against the frictional resistance upon the shorter friction plates. As the wedging elements move inwardly, the compressive action 40 upon the friction plates is gradually augmented by reason of the tapering form of the plates 55.

Upon release, the elements 47 and 50 are 45 urged backwardly by the central spring 87 and the wedging elements move backwardly with them under the influence of the springs 89, 91, and this action is facilitated by the tapering form of the plates 55.

50 As the release proceeds, the spring seat 101 engages the plates 49 and moves them back to normal position.

In draft, the action of the gear is the same, but in reverse direction of movement of the 55 various parts.

As the parts become worn by abrasion of the frictionally cooperating faces, the slack is taken up by the relative approach of the 60 wedge blocks 94, 99 without appreciably diminishing the power of the springs.

Various changes of details may be made within the scope of the invention and the 65 action of the gear would be the same if it were reversed in position or if the spread-

ing action of the wedges were horizontal instead of vertical.

I claim as my invention:

1. In a draft gear in combination, a chambered follower, an opposing plate follower, 70 two groups of intercalated friction plates within the chambered follower, one set of each group being anchored thereto against longitudinal movement and the other set being floating and normally projecting from the 75 chamber, a friction shoe engaging the inner plate of each group and having oppositely inclined wedging faces adjacent its ends, a pusher element seated on the plate follower and having lateral forwardly facing shoulders and a central stem having longitudinally extending side walls, a plate seated against each wall and having oppositely inclined wedging faces at its ends, a wedge block seated on each pusher shoulder and cooper- 80 ating with wedging faces of one of the shoes and one of the last named plates, wedge blocks cooperating with the wedging faces at the opposite ends of such elements, spring seats bearing on the last named wedge blocks 85 and engageable with the floating plates, springs reacting between such seats and the end wall of the chambered follower, and spring means reacting between the pusher stem and such wall. 95

2. In a draft gear in combination, a chambered follower, an opposing plate follower, 100 two groups of intercalated friction plates within the chambered follower, one set of each group being anchored thereto against longitudinal movement and the other set being floating and normally projecting from the chamber, a friction shoe engaging the inner plate of each group and having oppositely inclined wedging faces adjacent its ends, a 105 pusher element seated on the plate follower and having lateral forwardly facing shoulders and a central stem having parallel side walls, a plate seated against each wall and having oppositely inclined wedging faces at 110 its ends, such faces being less acute to the longitudinal axis of the gear than the wedging faces of the shoes, a wedge block seated on each pusher shoulder and cooperating with wedging faces of one of the shoes and one of the plates, wedge blocks cooperating 115 with the wedging faces at the opposite ends of such elements, spring seats bearing on the last named wedge blocks, and engageable with the floating plates, springs reacting between such seats and the end wall of the chambered follower, and spring means reacting between the pusher stem and such wall. 120

3. In a draft gear in combination, a chambered follower, an opposed follower, two 125 groups of intercalated friction plates located respectively on opposite sides of the gear axis, wedge means acting compressively on each group of plates, a pusher element interposed between the second named follower and the 130

- wedge means and having a central stem with parallel sides projecting between the two sets of wedge means, one of the elements of each set of wedge means being a wear-compensating element and being in sliding engagement with a side of the stem and spring means opposing the inward movement of the friction and wedging means, the wear compensating elements and the thrust element.
- 5 4. In a draft gear, in combination, a chambered follower, an opposed follower, two groups of intercalated friction plates located respectively on opposite sides of the gear axis, wedging means acting compressively on each 10 group of plates, a pusher element interposed between the second named follower and the wedge means and having a central stem with parallel sides projecting between the two sets of wedge means, one of the elements of each 15 set being a wear-compensating element slidably engaging one of the parallel sides of the stem, its wedging faces being relatively less acute to the axis of the gear than are the faces of other elements of the set, and spring means 20 opposing the inward movement of the friction and wedging means and of the thrust element.
5. In a draft gear in combination, a chambered follower, an opposed follower, two 25 groups of intercalated friction plates located respectively on opposite sides of the gear axis, wedge means acting compressively on each group of plates, a pusher element interposed between the second named follower and the wedge means and having a central stem 30 with parallel sides projecting between the two sets of wedge means, one of the elements of each set being a wear compensating element slidably engaging one of the parallel sides 35 of the stem, its wedging face being less acute to the axis of the gear than are the faces of other of the wedge elements, spring means 40 opposing the inward movement of the friction and wedging means, and independent 45 spring means opposing the inward movement of the thrust element.

In testimony whereof I affix my signature.
HERBERT E. TUCKER.
